Primary Examiner — Mimosa De(74) *Attorney, Agent, or Firm* — Cislo & Thomas, LLP(57) **CLAIM**

I claim the ornamental design for a chair, as shown and described.

DESCRIPTION

FIG. 1 is a perspective view of my chair;
 FIG. 2 is a front view thereof;
 FIG. 3 is a right side view, the left side (not shown) is a mirror image thereof;
 FIG. 4 is a rear view thereof; and,
 FIG. 5 is a top view of my chair.
